CLAIM

The ornamental design for a combined cordless string trimmer and edger, as shown and described.

DESCRIPTION

FIG. 1 is a perspective view of the combined cordless string trimmer and edger of the present invention;

FIG. 2 is a right side view of the design of the present invention;

FIG. 3 is a left side view of the design of the present invention;

FIG. 4 is a top view of the design of the present invention;

FIG. 5 is a bottom view of the design of the present invention;

FIG. 6 is a front view of the design of the present invention; and,

FIG. 7 is a rear view of the design of the present invention.
